UNITED STATES PATENT OFFICE

JOHN S. RICE, OF BIGLERVILLE, PENNSYLVANIA

APPARATUS FOR PACKING FRUIT AND THE LIKE

Application filed May 24, 1930. Serial No. 455,356.

This invention relates to a method and apparatus for packing fruit and the like, and it is an object of the invention to provide a method embodying the use of a device for directing or disposing inwardly the flaps of a basket liner after the filling of the basket and applied liner and before the application of the lid or cover and the cap generally associated with such lid or cover.

Another object of the invention is to provide a device which, in substantially one operation, effects an inward bending or flexing of flaps carried by an end of a basket liner.

The novel features of my invention will hereinafter be definitely claimed.

In order that my invention may be better understood, I will now proceed to describe the same with reference to the accompanying drawings, wherein:—

Figure 1 is a view in side elevation with a portion broken away illustrating a package before the flaps of the liner are flexed or disposed inwardly, the device for bending or flexing the flaps together with the associated cover or lid and cap for the package being shown in separated relation;

Figure 2 is a view in top plan of the structure as illustrated in Figure 1 with the flexing or bending device in working position with respect to the basket liner, the cover or lid and cap being omitted;

Figure 3 is a view partly in section and partly in side elevation illustrating a further step which may be employed in my improved method;

Figure 4 is a fragmentary view in top plan illustrating a flexing device constructed in accordance with a further embodiment of my invention;

Figure 5 is a view in top plan of a still further embodiment of flexing device, a second adjustment thereof being indicated by broken lines;

Figure 6 is a view in top plan of another embodiment of flexing device;

Figure 7 is an enlarged fragmentary sectional view illustrating the hinged connection between the sections of the device as illustrated in Figure 6;

Figure 8 is a view in top plan of a further embodiment of my invention;

Figure 9 is a detailed sectional view taken substantially on the line 9—9 of Figure 8.

It is now a well known practice in the packing of apples, peaches and the like to employ a method involving the use of a facing form upon which the top layer of fruit is arranged. After the placement of this layer of fruit upon the facing form a tub or shell with an inserted liner is mounted upon the facing form and surrounding the layer of fruit. The shell and applied liner above the layer of fruit on the facing form is then filled with fruit after which the tub or shell is removed. The liner is of a character to hold the fruit in column independent of this tub or shell so that an inverted basket may be readily disposed thereover.

The facing form and basket together with the fruit column are then upended and upon removal of the facing form a filled basket of fruit remains after which is applied in a well known manner a conventional cover or lid with generally a protecting cap.

It is recognized that if the liner is provided with flaps to be disposed or flexed inwardly over the top layer of fruit the value of the package is materially increased as such flaps serve as an effective means for protecting the outer or marginal row of fruit on the top layer from bruising or other injury.

To successfully use a liner with end flaps for the purpose just mentioned, it is important that means be provided to effect the desired inward disposal or flexing of the flaps of the liner after the filled basket has been upended but before the application of the lid or cover and its associated cap. In the embodiment of my invention as particularly illustrated in Figures 1 to 3 this is accomplished through the instrumentality of a device D. The device D, as herein disclosed, comprises a continuous annular member 1 of any desired material capable of efficient use for the purposes desired and which member 1 has an internal diameter sufficiently in excess of the open or top end of the basket B to readily pass downwardly thereover without hindrance or obstruction to such movement.

of the device being offered by the conventional basket handles 2.

Secured to the member 1 are the inwardly disposed flexible flaps 3 of a material whereby the same will readily yield or bend but which possesses an inherent characteristic of returning to normal position irrespective of the flexure to which the material may be subjected. These flaps 3 extend inwardly of the member 1 on a predetermined incline of a relatively small degree but which position the flaps normally maintain yet the flaps readily yield or give as the occasions of practice may require.

These flaps 3 are positioned with adjacent flaps in close proximity one to the other and are arranged substantially entirely around the member 1 except at diametrically opposed points where such flaps are omitted in order to readily compensate for the basket handles 2. These flaps 3 are also relatively long to assure the proper flexure or inward disposal of the flaps 4 arranged at an end portion of a basket liner L.

As is illustrated in Figure 1, it is to be noted that the flaps 4 of the liner L initially extend upwardly beyond the adjacent open end of the basket B and as the device D is placed upon the basket B, the flaps 3 of the device D will contact with the flaps 4 of the liner L and cause the same to bend or flex inwardly. The contact of the flaps 3 of the device D with the flaps 4 of the liner L as resisted by the basket content will serve to hold the device D in place upon the upper end of the basket and during that period the basket cap C and the basket lid or cover member M are properly arranged upon the basket B. It is then only necessary to press or force the device D downwardly or in a direction toward the bottom or closed end of the basket B and the flaps 3 will readily pass out from between the cap C or cover member or lid M and the basket content and upon such continued movement the device D may be entirely freed from the basket to be used in connection with another package. It is to be particularly noted that the device D through the instrumentality of these inwardly disposed flaps 3 provides a means whereby all of the flaps 4 of the liner L relative to a filled basket may be caused to flex or bend inwardly to assure the proper position or placement of the flaps 4 with respect to the basket content and the applied cover member or lid M with its associated cap C.

The embodiment of my invention as illustrated in Figure 4 is substantially the same as that illustrated in Figures 1, 2 and 3 except that at each of two diametrically opposed points the member 1a will be outwardly offset to provide hand grasps 5, said hand grasps also being of such form as to permit the same to readily pass over a handle member 2 so that after the de-

vice D^a in its entirety has been moved relative to the basket B to free the flaps 3a, the device can then be moved in an opposite direction to cause the device D^a to pass free of the basket at the end of the basket to which the cover member or lid has been applied.

In Figure 5 I illustrate an embodiment of my invention wherein the member 1' is split and is formed of a material possessing a certain degree of inherent resiliency whereby the member may be readily expanded when desired to facilitate its application or removal with respect to a basket. An expanded arrangement of the member 1' is indicated by broken lines in Figure 5. In this embodiment of my invention I also have the flaps 3' of materially less width than that of the flaps 3 and 3a previously referred to and which form of flaps 3' I find in practice can be employed with advantage. With this embodiment of my invention the member 1' may be expanded laterally with respect to the basket B a distance sufficient to permit the device, after being expanded, to be entirely freed from the basket upon movement of the device in an outward lateral direction or in an outward horizontal direction when considering the assembly as illustrated in Figure 1 of the drawings.

In the form of the invention as illustrated in Figure 6, the member 1'' comprises two substantially duplicate sections having adjacent ends hingedly connected, as at 6, said hinged connection being preferably of a spring type such as illustrated in Figure 7 so that the sections of the member 1'' will be normally at their relative inward movement and to which relative position said sections will return after being swung outwardly to expand the device or member 1'' to facilitate either the application or removal and more especially the removal of the device.

With this form of invention it has been found in practice that it is not essential that the flaps 3'' possess any high degree of resiliency or flexibility, which is equally true of the device as illustrated in Figure 5, as the lateral movement of either of these devices with respect to the basket B will permit its complete displacement relative to the basket without necessitating any appreciable flexing or bending of the flaps of the device.

In Figure 8 I illustrate an embodiment of my invention wherein the sections of the member 1b are hingedly connected, as at 7, while the outer or free end portion of one of the sections of the member is provided with a bolt or extending bar 8 which telescopes within a sleeve 9 carried by the free end portion of the second section. Arranged within this sleeve 9 is an expansion member 10, such as a coil spring, possessing sufficient tension to cause the free ends of the sections of the member 1b to automatically swing outwardly or separate. However, to

normally maintain the sections of the member 1b closed for proper application with respect to a package, I provide the free end portion of one of the sections with a catch 11 coacting with a suitable latch 12 carried by the free end portion of the second section. The member 1b is provided with the flaps 3b disposed inwardly thereof, the purpose of which being it is thought clearly understood from what has hereinbefore been described.

19 I claim:—

1. A device for bending end flaps of a liner inwardly thereof after the liner has been applied within a package comprising a member adapted to surround the package, and inwardly disposed flaps carried by said member for contact from above with the flaps of the liner.

2. A device for bending end flaps of a liner inwardly thereof after the liner has been applied within a package, comprising a member adapted to be disposed around the container, and flaps carried by said member extending inwardly thereof and adapted to contact 25 with the flaps of the liner.

3. As a new article of manufacture, a device for bending inwardly an end portion of a package liner after the liner has been placed in a container and the container has been 30 filled, said device comprising a member adapted to have surrounding placement with respect to the container and provided with means to contact with the liner for bending the liner inwardly upon movement of the 35 device in one direction with respect to the container.

4. A device for bending an end portion of a liner after the liner has been applied within a package comprising a member 40 adapted to be disposed around the package, and inwardly disposed flaps carried by said member for contact with the end portion of the liner, said flaps being of material whereby they will readily yield or bend but possessing an inherent characteristic of returning 45 to normal position irrespective of the flexure to which the material may be subjected.

5. A device for bending an end portion of a liner after the liner has been applied within a package comprising a member adapted to be disposed around the package, and inwardly disposed yieldable flaps carried by said member for contact with the end portion of 55 the liner, said flaps being of material whereby they will readily yield or bend but possessing an inherent characteristic of returning to normal position irrespective of the flexure to which the material may be subjected.

60 6. A device for bending an end portion of a liner inwardly thereof after the liner has been applied within a package comprising a member consisting of a plurality of hingedly connected sections, inwardly disposed flaps 65 carried by said sections, and means for con-

stantly urging said sections into closed relation.

7. A device for bending an end portion of a liner inwardly thereof after the liner has been applied within a package comprising a member 70 consisting of a plurality of hingedly connected sections, inwardly disposed flaps carried by said sections, means for constantly urging said sections into closed relation, and means for locking adjacent sections one to the other.

8. A device for bending an end portion of a liner inwardly thereof after the liner has been applied within a package comprising an expansible member adapted to be disposed around the package and inwardly disposed flaps carried by said member for contact with the end portion of the liner.

9. An apparatus for bending an end portion of a liner inwardly thereof after the liner has been applied within a package comprising a plurality of sections each having 85 inwardly disposed means for contact with the liner for bending inwardly a portion of the liner.

10. An apparatus for bending an end portion of a liner inwardly thereof after the liner has been applied within a package comprising a plurality of sections each having inwardly disposed means for contact with the liner for bending inwardly a portion of the liner, said sections having movement one 90 with respect to the other.

11. A device for bending an end portion of a liner after the liner has been applied within a package comprising a member adapted to be placed in surrounding position with respect to a package, said member having means for contact with an end portion of the liner for bending said end portion upon 95 movement of the member in one direction with respect to the liner.

In testimony whereof I hereunto affix my signature.
